ABSTRACT

A remote control system comprising, a remote transmitter for producing a remote control signal having different frequency components arranged in a predetermined order, and a receiver producing a plurality of control signals in response to the order of frequency components of the remote control signal.

Fig. 3**FIG. 6**## REMOTE CONTROL SYSTEM UTILIZING SIGNAL FREQUENCY SEQUENCE

BACKGROUND OF THE INVENTION

1. Field of the Invention

This invention relates generally to a remote control system, and more particularly to a remote control system avoiding a misoperation of the controlled circuit caused from a noise.

2. Description of the Prior Art

In prior remote control systems, a plurality of supersonic signals each having a different frequency are used to control a plurality of circuits, such as a power control circuit and a channel selecting circuit of a television receiver. Each frequency corresponds to one control circuit, but the control circuit may misoperate as a result of an acoustic noise such as the ringing of a telephone bell or the creaking of a door, because such sounds contain not only an audible signal component but also a supersonic signal component.

SUMMARY OF THE INVENTION

A remote control system utilizes a supersonic signal comprising two different frequency components arranged in a predetermined order, the order of the two frequencies being changed according to the circuit to be controlled. The remote control signal receiver has two frequency selecting means, two memory means and memory reset means; and the receiver produces a plurality of control signals in response to the order of two frequency components of the supersonic remote control signal.

It is an object of this invention to provide a remote control system avoiding a misoperation of the control circuit due to an acoustic noise.

Another object of this invention is to provide an improved remote control system which produces a control signal only when a received signal continues for a predetermined time period.

Further, still another object of this invention is to provide an improved remote control system which produces a control signal only when a received signal comprises two different frequency components arranged in a predetermined order.

Still a further object of this invention is to provide an improved remote control system avoiding misoperation of the control circuit due to momentary interruption of the supersonic remote control signal.

BRIEF DESCRIPTION OF THE DRAWINGS

FIG. 1 shows a block diagram of a remote control transmitter used in this invention;

FIG. 2A to FIG. 2F, inclusive, show waveforms produced at various parts of the remote control transmitter shown in FIG. 1;

FIG. 3 shows a schematic diagram of a remote control receiver used in this invention;

FIG. 4A to FIG. 4J and FIG. 5A to FIG. 5J show waveforms produced at various parts of the remote control receiver shown in FIG. 3;

FIG. 6 shows a schematic circuit diagram of another embodiment of the remote control receiver of this invention; and

FIG. 7A to FIG. 7J show waveforms produced at various parts of the remote control receiver shown in FIG. 6.

DESCRIPTION OF THE PREFERRED EMBODIMENT

FIG. 1 shows an example of a remote control transmitter used in the present invention. In the example of FIG. 1, control switches 1 and 2 may be push buttons, either of which would be pushed down in accordance with the circuit to be controlled. By way of example, when the control switch 1 is actuated, the power switch 10 of a television receiver is controlled, while when the control switch 2 is actuated, the channel selector of the television receiver is controlled.

The control switch 1 is connected to a monostable multivibrator 3, the output of which is supplied through an OR-circuit 7 to an oscillator 9 oscillating at a frequency f_1 , and is also supplied to a monostable multivibrator 4. The output from the monostable multivibrator 4 is applied through an OR-circuit 8 to an oscillator 10 which oscillates at a frequency f_2 . The output through the control switch 2 is connected to a monostable multivibrator 5. The output from the monostable multivibrator 5 is fed through the OR-circuit 8 to the oscillator 10 and to a monostable multivibrator 6, the output from which is fed through the OR-circuit 7 to the oscillator 9. The outputs from the oscillators 9 and 10 are amplified by an amplifier 11 and are fed to a speaker 12 which then produces a supersonic signal.

When the control switch 1 is actuated, a trigger pulse P_1 shown in FIG. 2A is produced from the control switch 1. The monostable multivibrator 3 is triggered by the trigger pulse P_1 and produces a positive pulse P_2 shown in FIG. 2B. The oscillator 9 is actuated by the pulse P_2 and produces a signal P_3 shown in FIG. 2C, the frequency of which is f_1 as mentioned above. The monostable multivibrator 4 is triggered by the trailing edges of the pulse P_2 to produce a pulse P_4 shown in FIG. 2E. The oscillator 10 is actuated by the pulse P_4 and produces a signal P_5 with a frequency of f_2 as shown in FIG. 2D. The signals P_3 and P_5 are amplified by the common amplifier 11, so that a supersonic wave signal F_1 with the frequency of f_1 and a supersonic wave signal F_2 with the frequency of f_2 are sequentially obtained from the speaker 12 as shown in FIG. 2F.

Alternatively, if the control switch 2 is actuated, the monostable multivibrators 5 and 6 achieve the same operation as in the case when the control switch 1 is operated except that the supersonic signal F_2 with the frequency of f_2 is produced first and is followed by the supersonic signal F_1 with the frequency of f_1 .

As is apparent from the above description, when either of the control switches 1 or 2 is actuated, there is obtained from the speaker 12 a supersonic signal comprising two different frequency components arranged in a predetermined order.

A remote control receiver according to the invention will be now described with reference to FIG. 3.

In FIG. 3, reference numeral 13 designates a microphone which may receive the supersonic signal emitted from the speaker 12 (which is not shown in FIG. 3). The corresponding electric signal from the microphone 13 is amplified by an amplifier 14. The output from the amplifier 14 is fed to a band pass filter 15a which may pass therethrough the frequency component f_1 and to a band pass filter 15b which may pass therethrough the frequency component f_2 . The output signals from the band pass filters 15a and 15b are fed to the base electrodes of transistors 18a and 18b which, together with

capacitors 19a and 19b connected between the ground and their collector electrodes, form detecting circuits 16a and 16b. The signals from the filters 15a and 15b are also connected to the base electrode of a transistor 20 in a noise eliminating circuit 17 that includes other elements such as capacitors, resistors, transistors and so on which will be described later.

The emitter electrode of the transistor 20 is grounded. A capacitor 21 is connected between the collector electrode of the transistor 20 and ground. The collector electrode of the transistor 20 is connected to the base electrode of a transistor 22 which has a grounded emitter electrode. The collector electrode of the transistor 22 is grounded through a capacitor 23C that has a relatively large capacity and is connected to a power source terminal 26 through a resistor 23R. The collector electrode of the transistor 22 is further connected to the base electrode of a transistor 24 which has a grounded emitter electrode. A capacitor 25 is connected between the collector electrode of the transistor 24 and the ground. Either of signals with frequencies f_1 and f_2 is detected by the transistor 20 and the capacitor 21. The transistor 24 is made conductive by a signal that continues for a time period longer than a predetermined time period which is determined by the resistor 23R and the capacitor 23C.

The emitter electrodes of the transistors 18a and 18b forming the detecting circuits 16a and 16b are both connected to the collector electrode of the transistor 24 of the noise eliminating circuit 17. The output signal from the detecting circuit 16a is applied through a diode to a set terminal S_1 of a memory circuit, for example, a flip-flop circuit 27a, while the output signal from detecting circuit 16b is applied through a diode to a set terminal S_2 of a flip-flop circuit 27b. Reset terminals R_1 and R_2 of the flip-flop circuits 27a and 27b are supplied with a negative, differentiated pulse produced by differentiating the output from the noise eliminating circuit 17 by a differentiating circuit 28.

The flip-flop circuit 27a memorizes the fact that the supersonic wave signal F_1 with the frequency f_1 is received and is connected at its output terminal P_1 to one of the input terminals of an AND-circuit 29, while the flip-flop circuit 27b memorizes the fact that the supersonic wave signal F_2 with the frequency f_2 is received and is connected at its output terminal P_2 to the other input terminal of the AND circuit 29. The output signal from the AND circuit 29 is applied to the base electrodes of NPN-type transistors 30a and 30b, respectively. The emitter electrode of the transistor 30a is connected to the output terminal of the detecting circuit 16b at the collector electrode of the transistor 18b. Only when the output of the AND circuit 29 is 1 and the output of the detecting circuit 16b is 0 is the transistor 30a made conductive to provide a 0 at a control signal output terminal 31a, which is connected to the collector electrode of the transistor 30a. The emitter electrode of the transistor 30b is connected to the output terminal of the detecting circuit 16a at the collector electrode of the transistor 18a. A control signal output terminal 31b is connected to the collector electrode of the transistor 30b.

A description will be now given of the operation of the receiver shown in FIG. 3.

Firstly, the case in which the supersonic signal F_1 with the frequency f_1 and then the supersonic signal F_2 with the frequency f_2 are transmitted in that order from

the transmitter will be now described with reference to FIG. 4A. In such a case, the transistor 24 of the noise eliminating circuit 17 becomes conductive after a noise eliminating time period T_n (refer to FIG. 4B) which is determined by the resistor 23R and the capacitor 23C has lapsed from the time the supersonic signals shown in FIG. 4A begin to be received, so that the transistor 24 produces at its collector electrode a signal of 0 level as shown in FIG. 4B. The signal is differentiated by the differentiating circuit 28 to be a reset pulse shown in FIG. 4C which is fed to the flip-flop circuits 27a and 27b at their reset terminals R_1 and R_2 , respectively. The frequency of the supersonic signal F_1 which is received firstly is f_1 , so that only the band pass filter 15a delivers an output signal which is fed to the base electrode of the transistor 18a of the detecting circuit 16a. At this time, since the transistor 24 is made conductive, as mentioned above, the detecting circuit 16a is capable of being operated. Accordingly, the detecting circuit 16a produces a signal of 0 level shown in FIG. 4D. During this interval, the detecting circuit 16b is supplied with no signal, its output signal remains at the 1 level.

The flip-flop circuits 27a and 27b are reset by the reset pulse shown in FIG. 4C, but the flip-flop circuit 27a has been continuously supplied, at its set terminal S_1 , with the output signal of 0 level shown in FIG. 4D from the detecting circuit 16a. As a result, the flip-flop circuit 27a is set immediately after the reset pulse has disappeared and hence it produces at its output terminal P_1 an output signal of 1 level shown in FIG. 4F. Meantime, the flip-flop circuit 27b is maintained in the reset state since the output signal from the detecting circuit 16b is kept at the 1 level. Accordingly, at the output terminal P_2 of the flip-flop circuit 27b there is obtained an output signal of 0 level shown in FIG. 4G. Therefore, the output from the AND circuit 29 drops to the 0 level as shown in FIG. 4H and the signals at the output terminals 31a and 31b remain at the 1 level, as shown in FIGS. 4I and 4J.

When the supersonic signal F_2 with the frequency f_2 is received, only the band pass filter 15b delivers an output signal, which is supplied to the base electrode of the transistor 18b of the detecting circuit 16b. At this time, since the transistor 24 remains conductive and the detecting circuit 16b can conduct. Accordingly, the detecting circuit 16b produces a signal of 0 level shown in FIG. 4E, and the flip-flop circuit 27b is set to produce at its output terminal P_2 an output signal of 1 level shown in FIG. 4G. At this time, the output signal at the output terminal P_1 of the flip-flop circuit 27a is also 1 in level, so that the level of the output signal from the AND circuit 29 as shown in FIG. 4H becomes 1. Accordingly, a positive bias is applied to the base electrodes of the transistors 30a and 30b, respectively. At this time, however, the transistor 18b is conductive but the transistor 18a is conductive, so that only the transistor 30a is made on and hence the level of an output signal delivered to the output terminal 31a becomes 0 as shown in FIG. 4I. However, the level of an output signal delivered to the output terminal 31b remains 1 as shown in FIG. 4J.

When the emission of the supersonic signal F_2 with the frequency of f_2 is stopped, the transistor 18b becomes non-conductive with the result that the transistor 30a is also made non-conductive and the level of the output signal delivered to the output terminal 31a becomes 1 as shown in FIG. 4I.

Next, a description will be given of the case in which the supersonic signal F_2 with the frequency f_2 and then the supersonic signal F_1 with the frequency f_1 which are shown in FIG. 5A are transmitted in that order from the transmitter. In such a case, the transistor 24 of the noise eliminating circuit 17 is made conductive after the noise eliminating time period T_{11} has lapsed from the time when the supersonic signal begins to be received as in the case that the supersonic signal shown in FIG. 4A is received, so that a signal of 0 level shown in FIG. 5B is produced at the collector electrode of the transistor 24. This signal is differentiated by the differentiating circuit 28 to be a reset pulse shown in FIG. 5C which is fed to the reset terminals R_1 and R_2 of the flip-flop circuits 27a and 27b. Since the frequency of the supersonic signal received firstly is f_2 , only the band pass filter 15b delivers an output signal, which is applied to the base electrode of the transistor 18b of the detecting circuit 16b. At this time, since the transistor 24 is conductive as mentioned above, the detecting circuit is operable. Accordingly, the detecting circuit 16b produces the signal of 0 level shown in FIG. 4E. At this time, the detecting circuit 16a is supplied with no signal, so that its output signal is kept at the "1" level as shown in FIG. 5D. The flip-flop circuits 27a and 27b are reset with the reset pulse shown in FIG. 5C, but since the set terminal S_2 of the flip-flop circuit 27b is continuously supplied, with the output signal of 0 level from the detecting circuit 16b as shown in FIG. 5E, it is set immediately after the reset pulse has disappeared, thereby to produce at its output terminal P_2 an output signal of 1 level shown in FIG. 5G. Meanwhile, since the flip-flop circuit 27a is kept in its reset state due to the fact the output from the detecting circuit 16a remains at the 1 level, an output signal of 0 level shown in FIG. 5F is delivered to the output terminal P_1 of the flip-flop circuit 27a. Accordingly, the level of the output signal from the AND circuit 29 becomes 0, as shown in FIG. 5H, and the output signals at the output terminals 31a and 31b remain 1. Thereafter, when the supersonic signal F_1 with the frequency f_1 is received, only the band pass filter 15a delivers an output signal which is applied to the base electrode of the transistor 18a. At this time, since the transistor 24 is still conductive, the detecting circuit 16a is operable. Accordingly, the detecting circuit 16a produces an output signal of 0 level shown in FIG. 5D. Thus, the flip-flop circuit 27a is set to produce at its output terminal P_1 an output signal of 1 level shown in FIG. 5F. At this time, the level of the output signal at the output terminal P_2 is also 1, so that the level of the output from the AND circuit 29 becomes 1, as shown in FIG. 5H. As a result, the positive bias is applied to the base electrodes of the transistors 30a and 30b, respectively. At this time, the transistor 18a is conductive, but the transistor 18b is not, so that only the transistor 30b is made conductive. For this reason, as shown in FIG. 5J, the output signal at the output terminal 31b is at the 0 level, but the output signal at the output terminal 30a remains at the 1 in level as shown in FIG. 5I.

When the emission of the supersonic signal F_1 with the frequency f_1 is stopped, the transistor 18a becomes non-conductive, and hence the transistor 30b also becomes non-conductive. As a result, the level of the output signal at the output terminal 31b becomes 1.

As may be apparent from the above description, with this invention if two supersonic signals are transmitted

in the order F_1 and F_2 with frequencies f_1 and f_2 , the level of the output signal at the output terminal 31a becomes 0 within the predetermined time period, while if the supersonic signals are transmitted in the order F_2 and F_1 , the level of the output signal at the output terminal 31b becomes 0 within the predetermined time period. On the other hand, if no supersonic signal is received, the output terminals 31a and 31b both remain at the 1 level. In a embodiment of FIG. 3, it is defined that the control signal is produced when the output signal at either the output terminal 31a or the output terminal 31b drops to the 0 level.

In general, since a noise appears during a relatively short time period, in the embodiment of FIG. 3 the noise eliminating circuit 17 is provided to operate the system only in response to a signal which continues for a time period longer than a predetermined time period. This avoids any misoperation which may be caused by the noise.

Further, with this invention the system is operated only when supersonic wave signals with different frequencies are received in a predetermined order, so that there is almost no possibility that misoperation can occur. The reason is that no natural noises with such a characteristic mentioned as above exist.

FIG. 6 shows another embodiment of a remote control receiver according to this invention. In the embodiment of FIG. 6, a remote control signal, which is obtained from the microphone 13 by converting a supersonic signal to the corresponding electric signal, is applied through the amplifier 14 and an emitter-follower transistor 32 to a band pass filter 33a that passes a signal component with the frequency f_1 and to a band pass filter 33b that passes a signal component with the signal f_2 , respectively. A detecting circuit 34a which consists of a diode 39, a resistor 40 and a capacitor 41 receives the output of the band pass filter 33a to produce a positive detected output signal which is then applied to a noise eliminating circuit 45a consisting of transistors 42, 43, a resistor 44R and a capacitor 44C that has a relatively large capacity. The noise elimination by the noise eliminating circuit 45a is as follows. When the output of the detecting circuit 34a is fed to the base electrode of the transistor 43, the transistor 43, which is normally conductive becomes non-conductive and the potential at the connection point between the collector electrode of the transistor 43 and the capacitor 44C increases gradually. In this case, the time constant of the resistor 44R and the capacitor 44C is large enough so that, if the received signal is an intermittent one, such as a noise signal, the potential at the connection point between the collector electrode of the transistor 43 and the capacitor 44C will not increase to such a level to make a following transistor 47a. Thus, the noise component is eliminated. The connection point between the collector electrode of the transistor 43 and the capacitor 44C in the noise eliminating circuit 45a is connected through a diode 46 with a polarity shown in the figure to the base electrode of a transistor 47a which forms a flip-flop circuit 35b together with a transistor 47b.

The supersonic signal with the frequency f_2 similarly passes through the band pass filter 33b and then is detected by a detecting circuit 34b. The output signal from the detecting circuit 34b is fed to a noise eliminating circuit 45b the output of which is memorized in a flip-flop circuit 35b. The band pass filter 33b, detecting

circuits 34b, noise eliminating circuit 45b and flip-flop circuit 35b are constructed to be substantially similar to the circuits 33a, 34a, 45a and 35a, respectively, so that their construction is not described and shown for the sake of brevity.

The output of the flip-flop circuit 35a and the output of the noise eliminating circuit 45b are applied to an AND circuit 36a the output terminal of which is connected to a control signal output terminal 37a, while the outputs of the flip-flop circuit 35b and the noise eliminating circuit 45a are applied to an AND circuit 36b the output terminal of which is connected to a control signal output terminal 37b. The time constant (discharging time constant) of the detecting circuits 34a and 34b is selected to be relatively short so as to eliminate noise components by the following noise eliminating circuits 45a and 45b, respectively.

A reset circuit 48 that consists of a resistor 50, a capacitor 51 of relatively large capacity a transistor 52 and acts to reset both the flip-flop circuits 35a and 35b simultaneously. The output terminals of the detecting circuits 34a and 34b are connected together to the reset circuit 48 through diodes 49a and 49b with the polarities shown in the figure. The connection point between the diodes 49a and 49b is grounded through the parallel connection of the resistor 50 and capacitor 51 and connected to the base electrode of the transistor 52 through a resistor. The collector electrode of the transistor 52 is connected to the power supply terminal 26 and its emitter electrode is grounded. The collector electrode of the transistor 52 in the reset circuit 48 is connected forming to the emitter electrode of the transistor 47a forming and similarly to the corresponding transistor (not shown) of the flip-flop circuit 35b. In this case, the discharging time constant of the reset circuit 48 determined by the resistor 50 and capacitor 51 is long enough as compared with that of the detecting circuits 34a and 34b.

A description will be now given on the operation of the embodiment shown in FIG. 6 with reference to FIG. 7A to FIG. 7J.

Firstly, the case that the supersonic signal F_1 with the frequency f_1 and then the supersonic signal F_2 with the frequency f_2 shown in FIG. 7A are received will be described. When the supersonic signal F_1 is received, the band pass filter 33a tuned to the frequency f_1 , permits the detecting circuit 34a to an output signal of "1" level shown in FIG. 7B. The discharging time constant of the detecting circuit 34a is selected to be short, so that the transistors 42 and 43 of the noise eliminating circuit 45a immediately perform their on-off operations in accordance with the existence of the remote control signal. Accordingly, when the supersonic signal F_1 is received, the transistor 43 is made non-conductive immediately, but the potential at the collector electrode of the transistor 43 rises gradually as shown in FIG. 7C due to the resistor 44R and capacitor 44C and, after the lapse of the time T_n reaches the level capable of making the transistor 47a of the flip-flop circuit 35a conductive. When this happens, the transistor 52 of the reset circuit 48 is made conductive by the remote control signal and its collector potential drops to the 0 level, as shown in FIG. 7J, so that the flip-flop circuit 35a is made operable. Accordingly, the transistor 47a becomes conductive and hence the collector potential of the transistor 47b is held at the 1 level, as shown in FIG. 7D. Since no signal is fed to the flip-flop circuit

35b in this state, its output signal remains at the 0 level and hence the output at the output terminal 37b also remains at the 0 level.

Thereafter, when the supersonic signal F_2 is received, the band pass filter 33b tuned to the frequency f_2 passes the signal to permit the output of the detecting circuit 34b to change to the 1 level as shown in FIG. 7E. As in the case of receiving the supersonic signal F_1 , the output of the noise eliminating circuit 45b increases gradually as shown in FIG. 7F after the supersonic signal F_2 is received. After the predetermined time period T_n has lapsed, the output of the flip-flop circuit 35b changes to the 1 level as shown in FIG. 7G. Accordingly, during a time interval within which the output of the flip-flop circuit 35a is 1 and the output of the noise eliminating circuit 45b is also 1, there is obtained at the control signal output terminal 37a an output signal of the 1 level shown in FIG. 7H. At this time, since the transistor 43 of the noise eliminating circuit 45a is in on the conductive state, its collector potential becomes 0 and the output at the control signal output terminal 37b becomes 0 irrespective of the state of the flip-flop circuit 35b.

When the reception of the supersonic signals is stopped, the base potential of the transistor 52 of the reset circuit 48 decreases gradually in accordance with the discharging time constant determined by the resistor 50 and the capacitor 51, as shown in FIG. 7I, and after a predetermined time period has lapsed the transistor 52 becomes non-conductive. Thus, the collector potential of the transistor 52 becomes 1 as shown in FIG. 7J and hence the flip-flop circuits 35a and 35b are reset. That is, when the supersonic signal F_1 is received and then the supersonic signal F_2 is received, an output 1 signal is obtained at the control signal output terminal 37a only. On the other hand, when the supersonic signal F_2 is received first and then the supersonic signal F_1 is received, an output 1 signal is obtained at the control signal output terminal 37b only. The operation of the circuit in this case is substantially same as that described above, so that its description is omitted for the sake of simplicity.

Since the transistor 52 of the reset circuit 48 is kept non-conductive when no signal is fed to the reset circuit, the outputs of the flip-flop circuits 35a and 35b are both kept at 0 and hence the outputs at the control signal output terminals 37a and 37b are also kept at 0.

In the embodiment shown in FIG. 6, it is defined that the control signal is generated when the output at the control signal output terminal 37a or 37b becomes 1.

With the embodiment of FIG. 6, the misoperation which may be caused by noises can be avoided by the provision of the noise eliminating circuits 45a and 45b as in the case of the embodiment shown in FIG. 3.

Further, in the embodiment of FIG. 6, the time constant of the reset circuit 48 is selected to be longer than that of the detecting circuits 34a and 34b, so that even if a remote control signal received by the intervention of a reflected supersonic signal on the ambient, which is a normal remote control signal, is temporally interrupted, the flip-flop circuits are prevented from being erroneously reset.

It will be apparent that many modifications and variations could be effected by those skilled in the art without departing from the spirit and scope of the novel concepts of the present invention.

We claim as our invention:

1. A remote control system for remotely controlling an apparatus in response to a remote control signal having a plurality of different frequency components arranged in a predetermined selection of orders, said system comprising:

- a. means for receiving the remote control signal transmitted thereto;
- b. frequency selecting means for selecting the different frequency components of said received remote control signal with different frequencies and producing a plurality of selected output signals corresponding to said different frequency components, respectively;
- c. means for memorizing one of said selected output signals;
- d. first gating means for gating an output of said memorizing means in response to a subsequent one of said selected output signals; and
- e. second gating means comprising first and second control signal output terminals and being connected to said first gating means to be enabled by the output of said first gating means during the occurrence of said subsequent one of said output signals and being gated in response to said subsequent one of said selected output signals to supply an output signal through said first output terminal when a first one of said frequency components occurs first and through said second output terminal when a second one of said frequency components occurs first.

2. A remote control system for remotely controlling an apparatus recited in claim 1, wherein said remote control receiver means further comprises means for resetting said memorizing means in response to a disappearance of said remote control signal.

3. A remote control system for remotely controlling an apparatus in response to a remote control signal having two different frequency components arranged in a predetermined order, said system comprising:

- a. means for receiving the remote control signal transmitted thereto;
- b. frequency selecting means for selecting the different frequency components of said received remote control signal with the different frequencies and producing two selected output signals corresponding to said different frequency components, respectively;
- c. first means for memorizing one of said selected output signals;
- d. second means for memorizing the other of said se-

lected output signals;

- e. first gating means connected to said first memorizing means and to the frequency selecting means for selecting the other of said selected output signals for gating an output signal of said first memorizing means in response to an output signal from said first memorizing means and to a signal corresponding to the other of said selected output signals; and
- f. second gating means connected to said second memorizing means and to the frequency selecting means for selecting the first of said selected output signals for gating an output signal of said second memorizing means in response to an output signal from said second memorizing means and to a signal corresponding to the one of said selected output signals.

4. A remote control system for remotely controlling an apparatus recited in claim 3, wherein said frequency selecting means includes two band pass filters each having a different resonant frequency and two detecting circuits connected to said band pass filters, respectively, each of said detecting circuits comprising a time constant circuit.

5. A remote control system for remotely controlling an apparatus recited in claim 4, wherein said remote control receiver means further comprises first and second noise eliminating means connected, respectively, between said first detecting circuit and said first memorizing means and between said second detecting circuit and said second memorizing means for actuating the respective memorizing means only when the respective remote control signal remains within a predetermined period.

6. A remote control system for remotely controlling an apparatus recited in claim 5, wherein said noise eliminating means comprises a time constant circuit selected to be longer than the time constant of either of said detecting circuits.

7. A remote control system for remotely controlling an apparatus recited in claim 4, wherein said remote control receiver means further comprises means for resetting said first memorizing means and second memorizing means simultaneously in response to disappearance of said remote control signal.

8. A remote control system for remotely controlling an apparatus recited in claim 7, wherein said resetting means comprises a time constant circuit selected to be longer than the time constant of either of said detecting circuits.
